United States Patent Office.

J. J. ANDERSON, OF ROCHESTER, PENNSYLVANIA.

Design No. 3,055, dated May 26, 1868.

DESIGN FOR A COOK'S STOVE.

The Schedule referred to in these Letters Patent and making part of the same.

TO ALL WHOM IT MAY CONCERN:

Be it known that I, J. J. ANDERSON, of Rochester, in the county of Beaver, and State of Pennsylvania, have invented a new and original Design for Cook-Stoves; and I do hereby declare that the following is a full and exact description thereof, reference being had to the accompanying illustration, making part of this specification, and representing the stove in perspective.

The outline of the front, A, of the stove, is a combined concave and convex curve ogee from top to bottom, and toward the bottom it swells forward at α , from the corners toward the middle. The back, B, of the stove, is similar in outline to the front.

The oven-door C is of oval form, oblong horizontally.

The door D of the fire-chamber has its corners rounded, and it is somewhat wider at the top than at the bottom, regularly diminishing in width downward.

The whole configuration is represented to the eye in the illustration.

What I claim as my invention, and desire to secure by Letters Patent, is—

The configuration composing a design for a cook-stove, as represented and described.

The above specification of my new and original design for cook-stoves, signed by me, this tenth day of October, 1867.
